YOKE VISE

Clyde E. Wright, Elyria, Ohio, assignor to The Ridge Tool Company, North Ridgeville, Ohio, a corporation of Ohio

Application October 13, 1941, Serial No. 414,701

1 Claim. (Cl. 81—19)

This invention relates broadly to vises and more specifically to improvements in jaw holders for yoke vises.

Heretofore in the construction of yoke vises, such as are used for holding pipes, bars and other tubular objects, the adjustable jaw has usually been secured within the socket or housing member by a bolt or rivet extending through the jaw and socket member. Such an arrangement not only increases the cost of manufacture of the vise, due to additional machining operations, but also tends to weaken the jaw member, thus materially reducing its effectiveness and efficiency.

One of the objects of the present invention resides in the provision of a yoke vise having a 15 slidable socket member of complementary sections which are secured together for locking the jaw member therein.

Another object of the invention is to provide the socket member with inwardly extending projections for engaging and retaining the jaw member therein.

Another object is to provide a jaw which is a solid member without openings therethrough.

Another object of the invention is to provide a 25 yoke vise which is of simple and rugged construction, economical of manufacture and reliable and efficient in operation.

Other objects and advantages more or less ancillary to the foregoing and the manner in which all the various objects are realized will appear in the following description, which considered in connection with the accompanying drawing, sets forth the preferred embodiment of the invention.

Referring to the drawing wherein the preferred 35 embodiment of the invention is illustrated

Fig. 1 is a front elevational view of the improved yoke vise;

Fig. 2 is a side elevational view of the yoke vise shown in Fig. 1;

Fig. 3 is a sectional view showing the socket or housing member with the jaw member disposed therein, the section being taken on a plane indicated by the line 3—3 of Fig. 1; and

Fig. 4 is a transverse sectional view of a fragmentary portion of the vise showing the jaw member secured within the socket, the view being taken on a plane indicated by line 4—4 of Fig. 1.

As shown in Fig. 1, the yoke vise comprises a 50 base or stationary frame member 10 having an adjustable clamp means 11 for securing the vise to a suitable support 12. An upper yoke member 14 is provided with bifurcated end portions 15 and 16 which engage a pair of diametrically

disposed, upwardly extending lugs 17 and 18 formed on the base member 10. The upper yoke member 14 is pivotally secured to the base member 10 by a bolt 19 extending through the bifurcated end portion 15 and the lug 17. A hook 21 pivotally mounted upon the upper yoke member 14, superjacent the bifurcated end portion 16 is adapted for quick detachable engagement with the lug 18 on the base for securing the yoke member to the base member 10. The bifurcated end portion 16 may be secured to the lug 18 by a pin, not shown, to facilitate the locking of the yoke upon the base member.

A hardened pipe engaging jaw 22 is formed on the base member 10 intermediate the lugs 17 and 18 and provides a cradle for the reception of a pipe 23. An upper jaw member 25 having recesses 26 in opposite ends is mounted within a socket or housing member formed of a pair of complementary cup sections 27 and 28. Inwardly extending abutments 29 are formed in the sections 27 and 28 for engaging the recesses 26 to aid in the retention of the jaw member 25 within the socket. The sections 27 and 28 of the socket are provided with a pair of aligned laterally extending arms 30 which terminate in angular lips 31 for slidably engaging opposite ways 32 provided by the sides of the yoke member 14. The jaw member 25 is securely locked within the cup sections 27 and 28 by bolts 33 extending through the arms 30 and having nuts threaded on the free ends for drawing the cup sections together.

Formed on the top surface of the cup sections 27 and 28 there are upwardly extending semi-cylindrical portions 35 having an inwardly projecting flange 36 defining a chamber 37 superjacent the jaw member 25. A screw threaded member 38 having an enlarged head 39 formed on one end extends through the apex of the upper yoke 14 and the enlarged head is positioned within the chamber 37 for engaging the jaw member 25. A suitable bar, not shown, is secured within the outer end of the member 38 to facilitate the movement of the socket or housing within the upper yoke 14.

In the use of the improved yoke vise the base member 10 is secured to a suitable support by the clamp 12 and the upper yoke member 14 is pivotally mounted upon the lug 17. A pipe or other tubular object 23 is then supported upon the jaw 22 subsequent to which the upper yoke 14 is pivoted about the lug 17 until the hook 21 engages the lower portion of the lug 18. Upon the engagement of the hook 21 with the lug 18, the screw threaded member 38 is rotated by the bar for

moving the socket member upon the ways 32 and the jaw 25 into engagement with the upper surface of the pipe or tubular object to insure the retention of the pipe within the vise stand.

The enlarged head 39 formed on the screw threaded member 38 engages the jaw member 25 for retaining the pipe within the vise. The force or pressure developed by the screw threaded member 38 for securing the pipe in the vise is applied directly to the jaw member 25 so that the socket member is practically devoid of any stress or strain and thus remains free to move on the ways 32. The only force or pressure that might be imparted to the socket member would be through the abutments 29 engaging the recesses 26 of the jaw member 25.

Although the foregoing description is necessarily of a detailed character, in order that the invention may be completely set forth, it is to be understood that the specific terminology is not intended to be restrictive or confining, and that various rearrangements of parts and modifications of detail may be resorted to provided they come within the scope of the claim.

I claim:

A yoke vise comprising a base member and a pipe engaging jaw carried thereon, an upper yoke

portion removably mounted on said base and having parallel guideways thereon, an upper jaw holding slide comprising a pair of complementary cup-shaped members each having pairs of laterally extending arms terminating in angular lips for slidably engaging the guideways on said yoke, the upper portions of said members being formed to provide a recess, a screw threaded actuating member extending in threaded engagement through said yoke and having an enlarged head connected to said member by a reduced stem, said head extending into said recess with said head in said recess, said members being formed with a pair of complementary portions to provide a rectangular socket extending transversely of said slide and having the ends provided with inwardly extending abutments, an upper jaw member carried in said socket and extending out of the socket toward said lower jaw and formed with recesses adapted for engagement with said abutments, said head on said stem arranged to engage the upper side of the jaw member in said socket and means extending through said slide members adjacent said socket for securing said members together and holding said jaw and head in said sockets and said slide on said yoke.

CLYDE E. WRIGHT.
